UNITED STATES PATENT OFFICE.

ROBERT RAINES, OF CHICAGO, ILLINOIS.

SELF-HEATING LUNCH OR DINNER PAIL.

SPECIFICATION forming part of Letters Patent No. 787,789, dated April 18, 1905.

Application filed June 16, 1904. Serial No. 212,776.

To all whom it may concern:

Be it known that I, ROBERT RAINES, residing at Chicago, in the county of Cook, State of Illinois, have invented an Improvement in 5 Self-Heating Lunch or Dinner Pails, of which the following is a specification.

My invention relates to self-heating lunch or dinner pails; and its object is to provide such an article which is particularly simple in 10 construction and highly desirable in use.

To this end the invention includes the combination and arrangement of component parts and the details of construction to be herein-after described, and particularly pointed out 15 in the claims.

In the accompanying drawings, which illustrate one exemplification of my invention, Figure 1 is a longitudinal sectional view of the same, parts being shown in elevation. 20 Fig. 2 is a detail sectional view of the body of the pail, and Fig. 3 is a detail view of the rear wall of the body or the slide which is used to form said wall.

The improved pail includes generally a body 25 portion, having a series of compartments formed therein, and a novel construction of flue, a lamp-stove associated with the body, a slide constituting one side of the body and removable therefrom, and a detachable top for 30 the body.

The body 1 has a flue-pipe 2 extending perpendicularly through the same, provided with a conical lower end 3 and a laterally-deflected intermediate portion 4. On one side of this 35 flue, in the lower portion of the body, a horizontal partition 5 is arranged, and above the latter a corresponding partition 6, thus forming two compartments 7 8, one of which may be used to hold a dessert, while the other may 40 provide a bread-receptacle. These two compartments are intended to be closed by the rear side wall 9 of the body, which is preferably formed by a slide removably mounted in the body for the purpose of giving access to 45 the two compartments. The slide 9 is preferably formed by a flat plate, which is movably mounted in suitable guideways 10, located in the edges of the sides 11 of the body. 50 Suitable pockets 12 are provided on the inner face of the slide to receive a knife, fork, and

spoon, these pockets being preferably formed by a pair of parallel straps having offset portions.

A beverage-compartment 13 is located in the lower portion of the body 1 on the opposite side of the flue 2 from the compartment 7 and is provided with a faucet 14 and with a filling-opening 15, the latter being located in its upper wall. Access to this opening for the purpose of filling the compartment 13 is 55 had through an opening 16 in the front wall of the body, which opening is normally closed by the front wall of a draw 17, which fits within the body between the upper wall of compartment 13 and a partition 18, and said 60 draw is provided with a rear wall shaped to conform to the adjacent portion of the pipe 2.

A saucer is intended to rest upon the partition 18, and directly above the latter a second partition 19 is arranged, having an opening through the same to receive and hold a cup which rests within the saucer. A third partition 20 is arranged above the partition 19 and is provided with a relatively larger opening, which is intended to receive a plate 75 and to give access to the cup and saucer when the plate is removed.

The body 1 is provided with a detachable cover 21, which is intended to be removed to give access to the dishes and to permit of the 80 removal of the slide 9.

A lamp-stove of any suitable construction is secured to the bottom of the body, has a font which provides a supporting-base for the latter, and has its burner arranged within 85 the conical portion 3 of the pipe 2. The font of the lamp is preferably attached to a flange 22 at the base of the body, this flange being provided with a series of openings 23, through which air may pass into the lower portion of 90 the pipe 2 to carry off therethrough any noxious odors arising from the burning of the lamp. By reason of the offset of the pipe the outlet thereof through the top 21 is brought to one side of the substantially centrally-arranged handle 24, and an increased 95 heating-surface is provided.

The compartment in the draw 17 may be used to hold meats or vegetables, or both.

The construction and operation of my in- 100

vention will be readily understood upon reference to the foregoing description and the accompanying drawings, and it will be appreciated that the parts and combinations recited may be varied within a wide range without departing from the spirit and scope thereof.

Having thus described my invention, what is claimed as new, and desired to be secured by Letters Patent, is—

1. In combination, in a lunch or dinner pail, a body portion having a pipe extending perpendicularly through the same and having a centrally-deflected portion, horizontal partitions on one side of said pipe in the lower portion of the body providing two compartments, a vertical wall removable from the body to give access to said compartments and provided with pockets to receive table implements, a beverage-compartment in the lower portion of the body having a filling-opening in its upper wall, a movable draw arranged above the beverage-receptacle removable to give access to the filling-opening thereof, a partition above said draw, a second partition above the first having an opening in the same, a third partition above the second having a relatively larger opening, a removable top, and a lamp-stove providing a base for the body.
2. In combination, in a lunch or dinner pail, a body portion having a pipe extending perpendicularly through the same and having a centrally-deflected portion, horizontal partitions on one side of said pipe in the lower portion of the body providing two compartments, a vertical wall removable from the body to give access to said compartments and provided with pockets to receive table implements, a beverage-compartment in the lower portion of the body having a filling-opening in its upper wall, a movable draw arranged above the beverage-receptacle removable to give access to the filling-opening thereof, a partition above said draw, a second partition above the first having an opening in the same, a third partition above the second having a relatively larger opening, a removable top, a flange at the base of the body provided with a series of openings, and a lamp-stove secured

to said flange having its burner extending up within the pipe; said openings in the flange providing means for the inlet of air into the lower portion of the pipe about the burner, substantially as described.

3. In a lunch or dinner pail, a body having a pipe extending perpendicularly therethrough provided with an offset intermediate of its length and provided with a conical lower end, a slide removably mounted in the body and providing one side wall thereof, compartments located in the lower portion of the body to one side of the pipe normally closed by said slide, a beverage-receptacle located in the lower portion of the body upon the opposite side of the pipe to said compartments, a series of dish-supporting partitions, a draw removably mounted in the body having a rear wall shaped to conform to the perpendicular and offset portions of the pipe, a removable top, and a lamp-stove secured to the base of the body, the font of said stove providing an enlarged base for the body and the burner of the stove extending into the conical portion of the pipe.

4. A lunch or dinner pail, comprising a body having a removable rear perpendicular wall and guideways at the rear of each of its side walls to receive said rear wall, a series of compartments arranged within the body, a detachable top having a carrying-handle arranged substantially centrally thereof, a lamp-stove secured to the bottom of the body and having its burner arranged substantially centrally of the same, and a flue-pipe extending perpendicularly through the body and having an offset intermediate portion to provide an increased heating-surface and to bring the upper end of said pipe to one side of said centrally-arranged handle.

In testimony whereof I have hereunto signed my name, in the presence of two attesting witnesses, at Chicago, in the county of Cook and State of Illinois, this 10th day of June, 1904.

ROBERT RAINES.
